REFRIGERATING APPARATUS

Homer E. Rosebrook, Greenville, Mich., assignor
to Gibson Electric Refrigerator Corp., a corpora-
tion of Michigan

Application August 9, 1933, Serial No. 684,421

11 Claims. (Cl. 62—126)

This invention relates to improvements in refrigerating apparatus and method and more especially relates to the evaporator or vaporizer.

My invention is particularly applicable to refrigerating apparatus of the so-called flooded-type in which lubricating oil is mixed with the refrigerant and separated therefrom by a difference in specific gravity. Such separation is usually obtained in the evaporator by allowing the oil to float up to the top of the liquid refrigerant.

Heretofore, however, such separation has caused the oil to form in a layer on the surface of the liquid refrigerant and this has interfered with or lessened the evaporation or boiling of the refrigerant.

Among the features of my invention is the provision of means and methods for drawing the oil off of a portion of the surface of the liquid refrigerant so that boiling at such portion is not impeded.

Another feature is the provision of means and method for concentrating oil on a portion of the surface of the liquid refrigerant while producing boiling under said portion, whereby the formation of said concentrated oil into a film is prevented and boiling of the refrigerant is not retarded.

Other features and advantages of my invention will appear more fully as I proceed with my specification.

In those forms of devices embodying the features of my invention shown in the accompanying drawings,—

Fig. 1 is a diagrammatic view of refrigerating apparatus; Fig. 2 is a vertical sectional view of the evaporator; Fig. 3 is a view taken as indicated by the line 3 of Fig. 2; Fig. 4 is a view similar to Fig. 2 showing a modified form of evaporator; Fig. 5 is a view similar to Fig. 2 showing another modification; and Fig. 6 is a view taken as indicated by the line 6 of Fig. 5.

In Fig. 1 which is merely diagrammatic I have made no attempt to show all the details of a complete refrigerating apparatus as these are all well known in the art. I have left out entirely, for example, the thermostatic control ordinarily employed as a showing of this is not necessary to illustrate my invention. In Fig. 1, 10 illustrates the usual compressor, 11 the motor therefor, 12 the condenser, and 13 a float controlled valve for controlling the flow of refrigerant from the compressor to the evaporator 14. The valve 13, for example, may be designed to pass only liquid refrigerant to the evaporator.

In the apparatus I have shown a refrigerant 20

and lubricating oil 21 adapted to separate because of a difference in specific gravity. The refrigerant, for example, may be sulfur dioxide and the lubricating oil some suitable oil with a lesser specific gravity.

The pipe 30 or 30' leading from the float valve 13 and/or the condenser 12 I shall refer to as the inlet pipe for the vaporizer. The pipe 31 leading from the vaporizer to the compressor I shall refer to as the outlet pipe and this pipe is adapted to withdraw oil and gaseous refrigerant from the header 40. For this purpose its end is preferably bevelled or slanted, as shown, and high enough so it will get oil and gas, but not liquid refrigerant.

In Figs. 1 to 3 I have shown a vaporizer with two sections here shown in the form of two headers 40 and 41 with the usual risers 42 and 43, respectively. This vaporizer, in its general construction, may resemble those now in common use. For example, it may be made of corrugated sheet metal spot welded to provide the necessary circulation and communication. The lower ends of the risers 42 may be connected together and likewise the lower ends of the risers 43, but there is no connection between the lower ends of the risers 42 and 43.

The inlet pipe for conducting lubricant oil and refrigerant to the vaporizer may enter at the bottom of the risers 43 as indicated by 30 or it may enter the header 41 as indicated by 30'. In the latter case, however, its end as shown by 30'' is taken to a point below the normal level 46 of the liquid refrigerant in the header 41.

50 indicates a tube with its upper end 50' in the header 41 at the normal level 46 of the liquid refrigerant therein. This tube is led downwardly (here shown as inside of one of the risers 43) and its lower end 50'' enters the bottom of the risers 42.

As the refrigerant and oil enter through the pipe 30 or 30' it flows into the header 41 filling this header to the level 46, and then overflowing into the tube 50. Since the upper end 50' of the tube 50 terminates at the level of the liquid refrigerant there is no blanket of oil lying on top of the liquid refrigerant in header 41. As the liquid comes in, it overflows through the pipe 50 into the bottom of the risers 42. Down this tube 50 the oil and some refrigerant will run practically all the time. As the liquid refrigerant and oil run down the tube 50, gathering boiling, it comes up the risers 42 and breaks up any film of oil tending to form in the header 40. This film tending to form and being broken up 55

by the boiling I have attempted to indicate by 21. As a result of this disturbance the retardation of the boiling by the oil is eliminated or lessened.

5 In Fig. 4, I have shown a modified form of evaporator showing the two sections in the form of a divided header. In general, however, the principles are the same. As here shown the single header 70 is divided by the partition into the 10 two sections or compartments 140 and 141, corresponding to the two separate headers 40 and 41 shown in Fig. 2. In Fig. 4, 130 is the inlet pipe and 131 the outlet pipe corresponding to the pipes 30 and 31 in Fig. 2. In the device of Fig. 4 15 the risers 142 and 143 correspond to the riser 42 and 43. The pipe 150, corresponding to the pipe 30, leads from the liquid level in chamber 141 to the bottoms of the risers 142. When these 20 corresponding parts are noted the construction and operation of the device of Fig. 4 will be clear.

In Fig. 5, I have shown a vaporizer in which the section of the vaporizer from which the refrigerant is withdrawn, is relatively small. This section, for example, may be in the form of a 25 round tube separate from the rest of the vaporizer. As shown in Fig. 5, the two sections of the vaporizer are indicated by 240 and 241, the latter section being provided with the usual risers 242 and 243, said risers communicating at their lower 30 ends. The inlet pipe 230 enters at the bottom of the risers 243 of the section 241. 250 indicates a pipe leading from the liquid level in section 241 to the bottom of section 240. The construction and function of this pipe is the same 35 as or similar to those of pipe 50 above described. In the form of Fig. 5, 231 is the outlet pipe.

While I have shown and described certain 40 embodiments of my invention, it is to be understood that it is capable of many modifications. Changes, therefore, in the construction and arrangement may be made without departing from the spirit and scope of the invention as disclosed 45 in the appended claims, in which it is my intention to claim all novelty inherent in my invention as broadly as possible in view of the prior art.

What I regard as new, and desire to secure by Letters Patent, is:

1. An evaporator for refrigerating apparatus employing in a flooded system a mixture of liquid 50 refrigerant and lubricating oil adapted to separate by differences in specific gravity, including; two sections for containing refrigerant, each having a vapor space above the level of the liquid refrigerant therein; means for introducing a mixture of liquid refrigerant and oil into one of said sections; a conduit for drawing oil from the surface of the liquid refrigerant in said section, said conduit also permitting overflow of liquid refrigerant, said conduit leading to the other section 55 below the surface of liquid therein; and means for withdrawing oil and gaseous refrigerant from said other section.

2. An evaporator for refrigerating apparatus employing in a flooded system a mixture of liquid 60 refrigerant and lubricating oil adapted to separate by differences in specific gravity, including; two sections for containing refrigerant, each having a vapor space above the level of the liquid refrigerant therein; means for introducing a mixture 65 of liquid refrigerant and oil into one of said sections, below the surface of the liquid refrigerant therein; a conduit for drawing oil from the surface of the liquid refrigerant in said section, said conduit also permitting overflow of liquid 70 refrigerant, said conduit leading to the other sec- 75

tion below the surface of liquid therein; and means for withdrawing oil and gaseous refrigerant from said other section.

3. An evaporator for refrigerating apparatus employing in a flooded system a mixture of liquid 5 refrigerant and lubricating oil adapted to separate by differences in specific gravity, including; two sections for containing refrigerant, each having a vapor space above the level of the liquid refrigerant therein; means for introducing a mixture 10 of liquid refrigerant and oil into one of said sections; a conduit for drawing oil from the surface of the liquid refrigerant in said section, said conduit also permitting overflow of liquid refrigerant, said conduit leading to the other section 15 below the surface of liquid therein; and means for withdrawing oil and gaseous refrigerant from said other section.

4. An evaporator for refrigerating apparatus employing in a flooded system a mixture of liquid 20 refrigerant and lubricating oil adapted to separate by differences in specific gravity, including; two sections for containing refrigerant, each having a vapor space above the level of the liquid refrigerant therein; means for introducing a mixture 25 of liquid refrigerant and oil into one of said sections, below the surface of the liquid refrigerant therein; a conduit for drawing oil from the surface of the liquid refrigerant in said section, said conduit also permitting overflow of liquid 30 refrigerant, said conduit leading to the other section below the surface of liquid therein; and means for withdrawing oil and gaseous refrigerant from said other section.

5. The method of operating refrigerating apparatus of the flooded type containing oil and refrigerant adapted to separate by differences in specific gravity, including, concentrating oil on a part of the surface of the liquid refrigerant in the vaporizer, and producing localized boiling of 40 refrigerant under said oil, whereby said oil is broken up and prevented from forming a film.

6. The method as claimed in claim 5, in which the oil as it is broken up is withdrawn with gaseous refrigerant.

7. The method of operating refrigerating apparatus of the flooded type containing oil and refrigerant adapted to separate by differences in specific gravity, including, concentrating oil on a part of the surface of the liquid refrigerant in the vaporizer, drawing liquid refrigerant from a part of the surface of the liquid refrigerant in the vaporizer, passing said drawn liquid refrigerant through a relatively warm part of the vaporizer to induce boiling of the refrigerant, and discharging 55 said boiling refrigerant under said first mentioned concentrated oil.

8. The method of operating refrigerating apparatus of the flooded type containing oil and refrigerant adapted to separate by differences in specific gravity, including, concentrating oil on a part of the surface of the liquid refrigerant in the vaporizer, drawing liquid refrigerant and oil from a part of the surface of the liquid refrigerant in the vaporizer, passing said drawn liquid refrigerant and oil through a relatively warm part of the vaporizer to induce boiling of the refrigerant, and discharging 60 said boiling refrigerant under said first mentioned concentrated oil.

9. An evaporator for refrigerating apparatus 70 employing in a flooded system a mixture of liquid refrigerant and lubricating oil adapted to separate by differences in specific gravity, including; two sections for containing refrigerant, said sections being substantially on the same level, each 75

5 having a vapor space above the level of the liquid refrigerant therein; an inlet pipe entering one of said sections below the liquid level; an overflow pipe leading from the liquid level in said section to a point below the liquid level in the other section; and an outlet pipe with its end just above the level of the liquid refrigerant in said other section.

10. The method of operating refrigerating apparatus of the flooded type containing oil and refrigerant adapted to separate by differences in specific gravity, including drawing oil from a part 10 of the surface of the liquid refrigerant in the vaporizer to lessen retardation of boiling at said 15 part of said surface by the presence of oil thereon, transferring said oil to another part of the sur-

face of the liquid refrigerant, and withdrawing oil and gaseous refrigerant from said other part through a single conduit.

11. The method of operating refrigerating apparatus of the flooded type containing oil and refrigerant adapted to separate by differences in specific gravity, including drawing oil and liquid refrigerant from a part of the surface of the liquid refrigerant in the vaporizer to lessen retardation of boiling at said part of said surface by the presence of oil thereon by the presence of oil thereon, transferring said oil to another part of the surface of the liquid refrigerant, and withdrawing oil and gaseous refrigerant from said other part through a single conduit. 5 15
